UNITED STATES PATENT OFFICE.

ROBERT S. BLAIR, OF SOUND BEACH, AND BURLING D. WELLS, OF DANBURY, CONNECTICUT; SAID WELLS ASSIGNOR TO SAID BLAIR.

WARNING DEVICE.

Application filed July 12, 1921. Serial No. 434,113.

This invention refers to warning signals and more particularly to devices of such nature as may be used for giving warning of the approach of railroad trains to grade crossings.

One of the objects thereof is to provide a signal of simple construction but durable and reliable in action. Another object is to provide a signal which requires no auxiliary energy for its operation. Another object is to provide a signal which may be attached to one of the rails of a railroad track and adapted to be operated by the vibrations of the rail due to the train running upon that track thus announcing the approach of a train on the track to which the signal is attached while the train is yet at a considerable distance. Another object is to provide a signal of such construction as to be proof against tampering and which cannot be removed from the track except by a person possessing the key to its lock or by completely demolishing it. Another object is to provide a signal which will not be made inoperative by snow, rain or mud unless completely buried thereby. Another object is to provide a method of utilizing the vibrations of the rails of a railroad as a source of energy to operate a signal. Other objects will be in part obvious and in part pointed out hereinafter.

The invention accordingly consists in the features of construction, combinations of elements and arrangements of parts which will be exemplified in the structure hereinafter described and the scope of the application of which will be indicated in the following claims.

In the accompanying drawings in which is shown one of the various possible embodiments of this invention, Figure I is a side elevation in cross section of a signal fastened on the lower side of a standard railroad rail, the end of one of the ties which supports the rail is also shown. Figure II is a plan view in cross section of the signal shown in Figure I, the section being taken along the line 1-1 in the direction as indicated by the arrows in Figure I, showing the mechanism for rendering the signal inoperative. Figure III is a cross sectional view taken along the line 2-2 in Figure II in the direction as indicated by the arrows which shows part

of the controlling mechanism for rendering the signal inoperative. Figure IV is a plan view of the lever by means of which the signal may be made inoperative and the spring which holds the lever in either the on or off position but prevents the lever from taking any position midway of these two positions. Figure V is a modification, and is a plan view of the head of the bolts which secure the signal to the track. Figure VI is a side elevation in cross section of a signal fastened on the lower side of a standard railroad rail. Figure VII is a plan view in cross section of the signal shown in Figure VI, the section being taken along the line 3-3 in the direction as indicated by the arrows.

Similar reference characters refer to similar parts throughout in the various views of the drawings.

Turning now to Figure I we have one of the rails 10 of a railroad track having clamped to the lower surface of its base flange an exterior casing 11 by means of a plurality of bolts such as 12 which hook over the edge of the base flange of the rail 10 and their threaded ends passing through holes in the exterior casing 11 are secured by the nuts 13 which securely hold the exterior casing 11 up against the base flange. The bolts 12 are formed with square shoulders which bear against the edge of the base flange of the rail 10 and prevent them from being swung around out of engagement therewith thus making it impossible to remove the exterior casing 11 and the mechanism contained therein from the rail 10 except by removing the nuts 13. The lower end of the exterior casing 11 is formed with the flange bolted on to which is a horn 14 by means of screws such as 15. A lug 16 on the flange of the horn 14 is so formed as to engage with the flange on the lower end of the exterior casing 11 and diametrically opposite to this lug is provided an ear 17 through which and a hole in the adjacent portion of the flange upon the lower end of the exterior casing 11 is passed the bar of a padlock 18 which makes impossible the removal of the horn 14 from the exterior casing 11 except by removing the padlock 18, although the screws such as 15 have been removed. A screen 19 is riveted to the horn 14 by rivets such as 20 to prevent the in-

section of sticks and stones therein to stop the action of the signal. A small hole is drilled in the lowest part of the horn 14 to act as a drain. A case 21 flanged at its lower end has clamped thereon a thin metal diaphragm 22 by a ring 23 which is securely held thereon by screws such as 24 tapped into the case 21. A gasket such as 25 is placed on each side of the metal diaphragm 22 making a water tight joint therebetween and the case 21 and also protecting the metal diaphragm 22 from minor deformations due to the inequalities of the surfaces between which it is clamped. At the corners of the case 21 which is square in form are secured two lugs such as 26 formed on the inside of the exterior casing 11 by means of screws such as 27. A metal bellows 28, circular in form and spun from very flexible metal has secured to its upper end by sweating with solder or by some similar process a block 29 which is in turn fastened to the center of the inside surface of the end of the case 21 by means of flat headed screws such as 30, there being secured to the other end of the metal bellows 28 in a manner similar to which the block 29 was secured thereon a flange 31 which is fastened to the center of the inertia member 32 by screws such as 33 which pass through a flange 34 which is fastened to the end of the metal bellows 35 and which is similar in construction to the metal bellows 28 but which is much smaller in diameter, the other end thereof having fastened thereto a stud 36 which passes through a hole in the center of the metallic diaphragm 22 and is securely gripped thereto by a pair of lock nuts such as 37. A pair of gaskets such as 33 is interposed between the faces of the flanges 34 and 31 and the inertia member 32 making a tight joint therewith, a hole passes through the center of the flange 31, the inertia member 32 and the flange 34 affording a clear passageway between the metal bellows 35 and 28. The relative diameter of the metal bellows 35 and 28 determines the ratio of the movement of the metal diaphragm 22 which is fastened to the metal bellows 35 and the inertia member 32 which is fastened to the adjacent ends of the metal bellows 28 and 35; thus a relatively small movement of the inertia member 32 along the axis of the metal bellows 28 and 35 will result in a comparatively large movement of the metal bellows 35 and the metal diaphragm 22 secured thereto because of the necessity of the metal bellows 35 having to elongate to a considerable extent in order to change its volume to the same extent as that change which took place in the volume of the metal bellows 28, as they are both entirely filled with a fluid nearly incompressible and freezing at a very low temperature, for instance kerosene. A ring-shaped rubber bumper 39 is fastened to the inside of the

case 21 by screws such as 40 and is so located that in case the rail 10 to which the apparatus above described is fastened should receive a downward impulse of such degree as would threaten the safe operation of the signal above described the inertia member 32 would come into contact with the ring-shaped rubber bumper 39 thus preventing undue movement of the metal diaphragm 22 by reason of limiting the degree of deformation of the metal bellows 28. Turning now to Figure II we have a shaft 41 journaled in a boss 42 on the inside of the case 21 and having pinned onto the lower end thereof a bell crank 43 by means of a pin 44. Turning now to Figure III we have a shaft 45 journaled in a boss in the exterior casing 11 and has pinned on to its upper end by means of the pin 44 a hand lever 46, shaft 45 being flanged at its lower end and has driven therein a pair of pins such as 47 which engage with two holes in a similar flange on the end of the shaft 41, the shaft 41 and the shaft 45 are so located in the case 21 and the exterior casing 11 that their center lines coincide. A spring 48 has one end hooked around the stud 49 on lever 46, the other end thereof is hooked over a stud 50 in the exterior casing 11. Returning now to Figure II we have a pair of links such as 51 connected to the ends of the bell crank 43 by means of pins such as 52 their other end being secured to the ends of the latches 53 by similar pins. Split pins such as 54 pass through the ends of the pins 52 holding them securely in place in the ends of the links 51, the latches 53 and the bell crank 43. The other ends of the latches 53 are wedge-shaped on their opposing edges and being swiveled about a pair of pins such as 55 which are pressed into bosses such as 56 on the inside of the case 21 will engage with suitable grooves cut in the circumference of the inertia member 32 whenever the other ends of the latches 53 are swung out from each other by the rotation of the bell crank 43 in a proper direction, the motion of the bell crank 43 being carried to the ends of the latches 53 by the links 51. A split pin 54 is passed through the lower ends of the pins 55 preventing the latches 53 from dropping therefrom. Turning now to Figure IV we have a stud 57 secured in the exterior casing 11 against which stud 57 the hand lever 46 is firmly held by the action of the spring 48 one end of which is hooked over the stud 49 in the hand lever 46 and its other end is hooked over the stud 50 secured in the exterior casing 11. The center line of the spring 48 in the hand lever 46 as in the position shown in Figure IV lies to one side of the center line of the shafts 41 and 45 thus holding the hand lever 46 firmly against the stud 57, this position of the hand lever 46 corresponds to the position of the bell crank 120

43 and of the latches 53 and the connecting linkages in the position as shown in Figure II. When the hand lever 46 is up against the stud 57 the signal is consequently unlocked and will operate whenever the rail 10 to which the signal is attached should be caused to vibrate by the approach of a railroad train thereon. Turning now to Figure VI, said figure shows a form of the signal 10 above described in which the vibrations of the rail to which it is attached are amplified and transmitted to a diaphragm by mechanical means instead of by hydraulic means, as made use of in the form of signal previously 15 described. In Figure VI we have an exterior casing 11 fastened to the lower side of the base flange of the rail 10 by means of bolts such as 12 the heads of which hook over the edge of the base flange of the rail 20 10 and their threaded ends pass through holes in the upper end of the exterior casing 11 and have nuts such as 13 threaded thereon which upon being firmly screwed home securely hold the exterior casing 11 25 against the bottom of the base flange of the rail 10, a square shoulder on the shank of the bolts 12 just under the heads thereof engages with the edge of the base flange of the rail 10 and prevents the removal of the 30 exterior casing 11 therefrom by swinging the heads of the bolts 12 out from engagement with the base flange of the rail 10. The square shoulder just under the head of the bolts 12 is clearly shown in Figure V. A 35 case 21 having an opening in its right hand side has clamped over this opening a metal diaphragm 58 by means of the clamping ring 59 which is held against the outside surface of the metal diaphragm 58 by a plurality of screws such as 60 which pass therethrough and are tapped into the case 21, gaskets such as 61 being placed on each side of the metal diaphragm 58 thus making certain the maintenance of an air tight joint 40 between the metal diaphragm 58 and the walls of the case 21. An inertia member 62, see Fig. VI, is supported within the case 21 upon a plurality of springs such as 63 which nest in depressions in the two ends of the 45 inertia member 62 and bear against the adjacent ends of the case 21 thus supporting the inertia member 62 at a distance from each of the ends of the case 21. Four links such as 64 are swiveled at one end upon a 50 pair of long pins 65 which pass through lugs such as 66 integral with the inside surface of the case 21. The other ends of the links 64 engage with pins such as 67 which pass through holes in the side of the inertia member 62, the function of the links 64 is to 55 maintain parallelism between the center line of the inertia member 62 and the center line of the case 21. A ring-shaped rubber bumper 68 in axial alignment with the inertia member 62 is secured to the inside surface of the 60 upper end of the case 21 by means of screws such as 69 tapped into the case 21, their heads being countersunk deeply within the rubber bumper 68 so that whenever the inertia member 62 comes into contact therewith the screws 69 will not impede the absorption of the force of the blow by the rubber bumper 68. The springs such as 63 which are nested in depressions in the upper 65 end of the inertia member 62 pass through holes in the rubber bumper 68 provided so that they may get a firm bearing upon the end of the case 21. The lower end of the case 21 is closed by a cover 70 secured to the lower end thereof by screws such as 71 70 which are tapped into a flange on the bottom end of the case 21, a gasket 72 is interposed between the cover 70 and the case 21 to insure a water tight joint therebetween. The case 21 and the mechanism assembled therein is held within the exterior casing 11 by means of screws such as 71, the alternate screws which secure the cover 70 to the case 21 are not tapped into the case 21 but pass through the cover 70 and the flange on the bottom of the case 21 finally screwing into a lug 26 on the inside of the exterior casing 11 thus securely holding the case 21 to the exterior casing 11. By removing the alternate screws such as 71 which are 75 threaded into the lug 26 the case 21 and the mechanism contained therein may be removed as a unit from the exterior casing 11. Threaded into the center of the lower end of the inertia member 62 is a bushing 73 which may be locked to the inertia member 62 by means of a check nut 74, a toggle anchor 75 the lower end of which is circular in form passes through the bushing 73 and has 80 threaded on its lower end a check nut 76 which permits a locking of the toggle anchor 75 to the bushing 73 by screwing the check nut 76 tightly up against the lower end of the bushing 73, the lower end of the toggle anchor 75 is made square in form so that a wrench may be used to hold it from turning whenever the check nut 76 threaded thereon is loosened or tightened up. The upper end of the toggle anchor 75 which is considerably 85 larger than the round portion which passes through the bushing 73 and forms a shoulder which bears against the upper end thereof is slotted and provided with a clamping screw 77 which is threaded into one of the projections formed by the slotting thereof, a toggle 90 78 formed of a thin flexible strip of resilient material has the lower end thereof securely clamped in the slot of the toggle anchor 75 by the clamping screw 77. The upper end of the toggle 78 is clamped in a lug 79 on the inside of the upper end of the case 21 in a similar manner by a clamping screw 77, two pairs of blocks such as 80 are riveted to the toggle 78 by rivets such as 86 95 so that whenever flexion takes place therein 100 105 110 115 120 125 130

all the bending will be localized at three points, that is: immediately adjacent to the points of attachment of the toggle 78 to the toggle anchor 75 and the lug 79 and also at 5 the center of the length of the toggle 78 between the two pairs of blocks 80 where the shaft 81 which connects the metal diaphragm 58 thereto by means of two pairs of check nuts such as 82 threaded on the two ends of 10 the shaft 81 and securely fasten the respective ends thereof to the metal diaphragm 58, and the toggle 78. The cover 70 is provided with a hole at its center in co-axial alignment with the center of the bushing 73 and 15 is closed by means of a cap such as 83 which is fastened thereon by means of screws such as 60, a gasket 87 is interposed between the flange on the end of the cap 83 and the cover 70 to insure the maintenance of an air tight 20 joint therebetween. On the right hand side of the exterior casing 11 there is secured a horn 14 by means of screws such as 60, the mouth of which is closed by means of a screen 19 which is flanged over at its edge 25 and riveted to the horn 14 by means of rivets such as 20. This screen permits easy egress of all sound which is generated by the vibration of the metal diaphragm 58 which is directly in line therewith but at the 30 same time prevents the introduction of sticks and stones to block the movement of the metal diaphragm 58. A small hole 84 is drilled in the lower part of the horn 14 to permit any moisture which may enter the 35 horn 14 to drain therefrom without entering the interior of the exterior casing 11. The lower end of the exterior casing 11 is closed by a plate 85 secured thereto by means of screws such as 15. The removal of the plate 40 85 by anyone other than those who have authority to do so is prevented by passing the bar of a padlock 18 through a hole in the edge of the plate 85 and through a hole in the flange on the lower end of the exterior casing 45 11 which registers therewith, and a lug 86 on the upper side of the plate 85 which hooks over the inside edge of the flange on the lower end of the exterior casing 11 makes it impossible to remove the plate 85 even if 50 all the screws 15 have been removed therefrom until the padlock 18 has been unlocked by using a proper key. Turning now to Figure VII we have a pair of latches 53 swiveled upon a pair of pins 55 which are 55 mounted in bosses such as 56 which are integral with the inside surface of the case 21, the ends of these latches 53 are wedge-shaped in section along the edges adjacent to the inertia member 62 and upon the proper 60 manipulation of the handle 46 shown in Figure II engage with suitable grooves cut in the side of the inertia member 62 and prevent movement thereof relative to the case 21. The linkage connecting the handle 46 65 with the latches 53 is identical in design

both in the case of the hydraulic and mechanical forms of the signal above described and is consequently shown and described only with reference to the hydraulic form of the signal which was described above. 70

The operation of the hydraulic form of the apparatus above described is substantially as follows: The signal is bolted to the bottom of the base flange of the rail 10 as shown in Figure I, between two of the ties which support the railroad track of which the rail shown at 10 in Figure I is a part. In order to gain access to the nuts 13 on the ends of the bolts 12 it is necessary to remove the case 21 and the mechanism contained therein 75 from the exterior casing 11 which is accomplished by removing the screws 15 which secure the horn 14 to the lower end of the exterior casing 11 and upon unlocking the padlock 18 it is possible by swinging the left 80 hand end of the flange of the horn 14 downwardly to the right and finally disengaging the lug 16 from engagement with the flange on the lower part of the exterior casing 11 to completely remove the horn 14. The case 85 21 is now removed by unscrewing the screws 27 which pass entirely through the ring 23, the gaskets 25 and the flange on the lower end of the case 21 and secure the flange to the lug 26 on the inside surface of the exterior 90 casing 11. The screws such as 24 which fasten the ring 23 and the metal diaphragm 22 and its gaskets 25 to the case 21 are not disturbed thus the working mechanism proper 95 of the signal is removed from the exterior 100 casing 11 without destroying any of its adjustments. The exterior casing 11 is now held up against the bottom of the base flange of the rail 10 and the bolts 12 are inserted through the holes in the top of the exterior 105 casing 11 with their heads lapping over the edge of the base flange of the rail 10 and the nuts 13 are firmly screwed up by inserting a wrench into the casing 11, the square shoulder just under the head of the bolt 12 110 as shown in Figure V abuts against the edge of the base flange of the rail 10 and prevents the bolts 12 from turning as the nuts 13 are screwed up. The exterior casing 11 having 115 been securely fastened to the rail 10 the signal is reassembled by a procedure similar to that by which it was taken apart preparatory to its attachment to the rail 10 as above described. When inserting the case 21 into the exterior casing 11 it is essential that the 120 holes in the flange on the upper end of the shaft 41 should engage with the pins in the flange on the lower end of the shaft 45 as shown in Figure III otherwise it will be impossible for an employee of the railroad to 125 render the signal inoperative at such times when there is no need of a warning signal in the locality where the signal has been applied to the railroad track. As is well known, an approaching train sets up very 130

rapid vibrations of the rails so that the approach of a train to a place where the highway crosses a railroad track can be readily determined by listening to the hum of the 5 rails which is quite audible even when the train is beyond the range of vision. This signal has been designed to be operated by the vertical component of the vibration of the rail to the base of which it has been attached, although certain of the broader features of the invention are not limited to such use. The entire mechanism of the signal above described contained in the exterior casing 11 is rigidly connected with the rail 10 with the exception of the inertia member 32 which is flexibly supported by the metal bellows 28 and consequently as the rail 10 vibrates in that direction along the center line drawn through the two metal bellows 35 and 28 the inertia member 32 will tend to remain at rest while the remainder of the mechanism of the signal will follow the vibration of the rail 10. The inertia member 32 at best will not entirely remain at rest but will vibrate 25 with an amplitude which will be considerably less than that of the rail 10. Let us consider the rail 10 moving downward through one of its cycles of vibration, the inertia member 32 not being rigidly connected with the rail 10 will move downward to a lesser degree and even under certain conditions of vibration its downward movement during the downward movement of the rail 10 will hardly be discernible and will cause a 35 considerable shortening of the metal bellows 28 and a corresponding decrease in the volume thereof. The slight downward movement of the inertia member 32 and the appreciable downward movement of the case 40 21 may be considered as an appreciable movement towards each other and although the upper end of the metal bellows 35 which is connected to the inertia member 32 by means of the flange 34 and the screws 33 moves downward therewith, the increase in 45 the volume contained in the metal bellows 35 is very small compared with the decrease in volume in the metal bellows 28 and as the metal bellows 35 and the metal bellows 28 are 50 connected to each other by the passageway over the flanges 34 and 31 connected therewith a portion of the fluid contained in the metal bellows 28 will be driven down through the passageway into the metal bellows 35 and result in a considerable extension 55 thereof driving the metal diaphragm 22 downward by reason of the lower end of the metal bellows 35 being connected therewith by the stud 36 and the two lock nuts 37. When the rail 10 reaches the lowest point of 60 its downward movement during the cycle of its vibration under the action of an approaching train and starts on the return movement the inertia member 32 will lag 65 behind the rest of the mechanism contained in the exterior casing 11 and as there is thus set up a relative movement of the inertia member 32 away from the upper end of the case 21 an appreciable lengthening of the metal bellows 28 and a corresponding increase of its internal volume will take place 70 by reason of its upper end being secured to the case 21 which is moving upward and away from the inertia member 32 to which the lower end of the metal bellows 28 is fastened by means of the flange 31 and the screws 33. The resultant increase in volume of the metal bellows 28 will cause a slight drop in pressure therein resulting in the flow 75 of the fluid contained in the metal bellows 35 through the passageway connecting it with the upper metal bellows 28 and cause an appreciable shortening of the metal bellows 35 as its volume must diminish by an amount equal to the quantity of fluid which has 80 flowed up into the upper metal bellows 28 although the inertia member 32 at the present moment has a movement relative to the upper end of the case 21 downward therefrom resulting in a shortening of the lower metal bellows 35 the shortening of its axial length resulting therefrom is very much less than that resulting from the withdrawal of the fluid contained therein by the upper metal bellows 28 due to the fact that the upper metal bellows 28 has a very large diameter in comparison with the diameter of the lower metal bellows 35. The lower metal bellows 35 having been caused to shorten its 85 axial length quite appreciably as above described and its upper end being secured to the inertia member 32 by means of the flange 34 and the screws 33 which pass three-through and screw into the flange 31 thus holding the upper end thereof in a comparative state of rest with the case 21, a marked upward movement of the center of the metal diaphragm 22 will result from the stud 36 which is integral with the lower end of the metal bellows 35 moving upwardly therewith lifting the center of the metal diaphragm 22 by reason of its being secured to the center of the metal diaphragm 22 by the two lock nuts 37. From the above description of the operation of the signal it will be 90 seen that the vibration of the rail 10 will be greatly amplified and transmitted to the metal diaphragm 22 as the inertia member 32 in holding the adjacent ends of the metal bellows 35 and 28 approximately stationary 95 causing the fluid contained therein to flow from one to the other, a violent sound will be generated by the metal diaphragm 22 acting upon the air in the horn 14 and the noise thus generated will pass out through the 100 screen 19 which covers the end of the horn 14. The operation of the mechanical form of the signal above described and shown in Figures VI and VII of the drawings is sub- 105 110 115 120 125 130

stantially as follows: A train approaching upon the track to the base of one of the rails 10 of which is attached the signal shown in Figures VI and VII, will cause vibration 5 of the rail 10 to a degree depending upon the proximity of the train to the point on the track where the signal is attached. The vertical component of the vibration of the rail 10 will cause an up and down movement 10 of the exterior casing 11 which is securely fastened thereto, by the bolts 12 and all the mechanism of the signal which may be rigidly connected to the exterior casing 11 will vibrate in harmony with the rail 10. 15 The rail 10 vibrates in other directions than in the vertical plane but it is the vibrations which lie in this plane only that we are interested in as the signal above described is designed to make use of these vibrations 20 only. As the exterior casing 11 moves up and down with the rail 10 the inertia member 62 which is not rigidly connected in any way therewith tends to lag behind and also in addition to its lag the amplitude of vibration thereof will be considerably less than the amplitude of vibration of the exterior casing 11 and the rail 10 to which it is attached. 25

From the above description of the action 30 of the inertia member 62 it will be seen that the lower end of the toggle 78 which is rigidly connected to the inertia member 62 by means of the toggle anchor 75 which is in turn clamped in the bushing 73 by the lock nut 76, is held substantially in a state of rest while the upper end thereof which is clamped in the lugs 79 by the clamping screw 77 is subjected to all movements which the case 21 acquires through its rigid connection 35 with the exterior casing 11 and the rail 10 to which it is rigidly connected. As the distance between the two ends of the toggle 78 increases and diminishes due to the up and downward movement of the case 21 40 while the inertia member 62 remains substantially at rest it will cause a lateral movement of the toggle 78 which will be much greater in extent than the movement of the rail 10 and the parts of the signal connected 45 thereto due to the well known action of the ordinary toggle linkage construction which is embodied in this apparatus in the form of the toggle 78 constructed of a thin strip of resilient material. The degree of lateral 50 movement of the center of the toggle 78 and the shaft 81 and the metal diaphragm 58 which is connected to its right hand end by means of the check nuts 82 may be varied at will by moving the lower end of the toggle 78 where it is connected to the toggle anchor 75 up or down by loosening the check nuts 76 and 60 and then adjusting the position of the toggle anchor 75 by raising or 55 lowering the bushing 73 and the desired adjustment having been obtained the adjust- 60

ing means is securely locked again by screwing up the check nuts 76 and 60. To diminish the degree of amplification of the vibrations of the rail 10 during their transmission to the metal diaphragm 58 it is only 70 necessary to raise the bushing 73 as above described thus forming a more acute angle at the center of the toggle 78 thus a downward movement of the upper end of the toggle 78 while the lower end is held stationary will cause a smaller lateral movement of the shaft 81 than would be the case if the bushing 73 had been moved downward increasing the angle formed at the center of the toggle 78. As is well known, when the 75 two links of the toggle very nearly fall in the same straight line a very large movement of the connecting ends of the respective links in a direction perpendicular to a line passing through their other two ends will 80 result in a very small movement along that line and in the case where the two links of the toggle 78 form a rather acute angle with each other a lateral movement of the connecting ends of the two toggle links will 85 cause a much smaller movement of the other ends of the two toggle links in the direction of a line passing therethrough. Thus it will be seen that there is provided means 90 adapted to permit the adjustment of the sound which the signal above described has been designed to produce, permitting it to be used on rails of various degrees of rigidity and over which different weights of railroad equipment pass. The signal may 95 be adjusted by removing the plate 85 and the cap 83 as above described if it is desired to regulate the tone of the signal after it has been attached to the base of the rail 10. If the signal were subjected to very great 100 vibrations which would endanger the proper operation of the apparatus the inertia member 62 will come into contact with the rubber bumper 68 thus limiting its upward movement relative to the case 21 and preventing the metal diaphragm 58 from being ruptured, movement in a downward position relative to the case 21 could be retarded 105 by the toggle 78 straightening out.

The intensity of the sound generated by 110 the signal above described will rapidly increase as the train approaches the grade crossing or a point where the signal is attached to the track thus making it possible for one to readily tell whether the train is 115 approaching or receding from that point by listening for a few moments to the warning signal.

From the above it will be seen that there is 120 provided an art and an apparatus wherein the desired results are obtained.

As various possible embodiments might be 125 made in the illustrative apparatus above described and as various changes might be made in the art herein set forth it is to be 130

understood that all matter herein set forth or shown in the accompanying drawings is to be interpreted as illustrative and not in a limiting sense.

5. We claim:

1. The herein described art which consists in utilizing the vibration of a railway rail to vibrate one of two members relative to another, limiting said vibratory movement; 10 moving said members as a unit with the rail as it is depressed by the passage of a car wheel thereover, and utilizing said vibration to cause the operation of an alarm signal.

2. The herein described art which consists 15 in utilizing the vibration of a railway rail, amplifying the extent of such vibration in another member and utilizing the sound of vibration of the second member as an alarm.

3. The herein described art which consists 20 in utilizing the vibration of a railway rail to cause the vibration of another member, utilizing the sound caused by the latter vibration as an alarm and limiting the effect of depression of the rail upon the second member; 25 as a car wheel passes over the point at which the vibration of the rail is utilized.

4. In construction for alarm signals, in combination, a railway rail, a vibratory sound-producing member adapted to serve as an alarm, an actuating member mounted to be vibrated by said rail and to be moved therewith upon said rail being depressed by the passage of a car wheel thereover, and transmitting means interposed between said actuating member and said vibratory member adapted to cause the vibration of the latter with a greater amplitude than that of the vibration of said rail by the energy of vibration of the rail.

45 5. In construction for alarm signals, in combination, a railway rail, a vibratory sound-producing member adapted to serve as an alarm signal, and transmitting means interposed between said rail and said member composed of a series of connected physical bodies adapted to vibrate said member with an increased amplitude from the vibration of said rail.

50 6. In construction for alarm signals, in combination, a railway rail, a vibratory sound-producing member connected therewith to be operated thereby and means adapted to prevent excess effect upon said vibratory member, upon the rail being depressed by the passage of a car wheel thereover.

55 7. In construction for alarm signals, in combination, a vibratory member, a vibratory sound-producing member, a third member and means connected with said third member to transmit vibrations of said first member to said sound-producing member and utilize the inertia of the third member to form a relatively fixed point.

65 8. In construction for alarm signals, in combination, a railway rail, a vibratory

sound-producing member, a third member movable with respect to said rail and said sound-producing member and means connecting said rail and said sound-producing member to vibrate the latter from the vibrations of said rail and utilizing the inertia of said third member as a relatively fixed point of support. 70

9. In construction for alarm signals, in combination, a railway rail, a device operatively related to said rail comprising a member vibrated by the rail and a member adapted by its inertia to serve as a substantially fixed point with respect to which said first member moves, and an alarm signal adapted to be actuated on the vibration of said first member by said rail. 75 80

10. In construction for alarm signals, in combination, a railway rail, a device secured to said rail and comprising a member connected to be vibrated by the vibration of said rail, means on said device adapted to limit the amplitude of said vibration, whereby said device is depressed with said rail upon the depression of the rail by the passage of a car wheel thereover without excessive movement of said vibrated member, and an alarm signal connected with said device to be actuated upon said member being vibrated by said rail. 85 90 95

11. In construction for alarm signals, in combination, a railway rail, a device secured to said rail and comprising a member connected to be vibrated by the vibration of said rail whereby said device is depressed with said rail upon the depression of the rail by the passage of a car wheel thereover, a vibratory alarm signal, and means adapted to vibrate said alarm signals with an increased amplitude with respect to that of said rail upon said first member being vibrated by said rail. 100 105

12. In construction for alarm signals, in combination, a railway rail, a substantially enclosed casing secured to said rail and adapted to be depressed therewith upon the passage of a car wheel thereover, an alarm device, and means within said casing adapted to utilize the vibration of said rail to actuate said alarm. 110 115

13. In construction for alarm signals, in combination, a railway rail and an alarm device adapted to be actuated by the vibration of said rail, said alarm device being mounted in a substantially enclosed casing connected to said rail. 120

14. In construction for alarm signals, in combination, a rail, an alarm device, a connecting member, positively acting means adapted upon said rail vibrating to move said connecting member positively throughout a distance greater than the amplitude of vibration of the rail, and means adapted to utilize such movement to cause the actuation of said alarm device. 125 130

15. In construction for alarm signals, in combination, a railway rail, an alarm device, means connected to said rail adapted by the vibration of the latter to cause said alarm device to vibrate throughout a distance greater than the amplitude of vibration of said rail.
16. In construction for alarm signals, in combination, a railway rail, a casing connected thereto, an inner casing mounted within said first casing and having a vibratory member associated therewith, an alarm device, and means associated with said inner casing adapted to utilize the vibration of said rail to actuate said alarm.
17. In signalling apparatus, a device for causing an alarm signal to be operated comprising a casing secured to a rail to move therewith and containing a plurality of members one of which is relatively heavy and adapted to act by its inertia and thereby serve as a point of substantially fixed support for a portion of another of said members, which latter member is adapted to be vibrated by said rail with respect to
- said first member and by its vibration to cause the alarm to be actuated.
18. In construction for alarm signals, in combination, a railway rail, an alarm device adapted to be actuated by the vibration of said rail, a casing about said alarm device and secured to said rail and having an opening therein adapted to permit exit therefrom of sound waves from said alarm device, and screening means associated with said opening.
19. In construction for alarm signals, in combination, a railway rail, an alarm device adapted to be actuated by the vibration of said rail, a casing about said alarm device and secured to said rail and having an opening therein adapted to permit exit therefrom of sound waves from said alarm device, and means associated with said casing adapted to prevent access of rain to said alarm device.

In witness whereof, we hereunto subscribe our names.

ROBERT S. BLAIR.
BURLING D. WELLS.
